UNITED STATES PATENT OFFICE.

WILLIAM R. HUTTINGER, OF LANSDOWNE, PENNSYLVANIA.

ELECTRIC SWITCH.

Application filed December 29, 1923. Serial No. 683,514.

One object of this invention is to provide a novel form of terminal structure, particularly designed for use on high tension switches, which shall not only include means 5 for guiding a switch blade into proper engagement with a contact member, but shall also be of such form as to enclose and protect said member from accumulations of ice, snow or sleet which might render operation 10 of the switch difficult or impossible.

It is further desired to provide a novel form of protecting hood for a switch terminal which may be easily applied and which, while permitting the free engagement 15 of the switch blade with its cooperating fixed contact member, shall include portions designed to guide said switch blade prior to its engagement with the contact member so as to cause it to ultimately occupy such a position as will insure its proper relation therewith.

I also desire to provide a novel arrangement and mounting for the blade-actuating mechanism of a high tension switch, so designed as to maintain at a maximum the striking distances between parts at different potentials and at the same time effectually prevent short circuiting or grounding in the event of any of said actuating mechanism 30 getting disconnected or breaking.

These objects and other advantageous ends I attain as hereinafter set forth, reference being had to the accompanying drawings, in which,

35 Figs. 1 and 2 are respectively a front and a side elevation of a high tension switch constructed in accordance with my invention;

Fig. 3 is a side elevation of the sleet hood constituting part of my invention and certain of its associated parts;

Fig. 4 is a sectional elevation on the line 4-4, Fig. 3;

Fig. 5 is a rear elevation of the structure shown in Fig. 3; and

45 Fig. 6 is a plan of the device.

In the above drawings, 1-1 represent supporting structures upon each of which are mounted two stacks or series of high tension insulators 2 and 3, of which the first carries 50 a fixed contact 4 to which is hinged one end of a more or less elongated switch blade 5, preferably having the construction described and claimed in an application for U. S. Patent Serial No. 409,058, filed September 9,

55 1920 by Robert Renke. Such a switch blade consists of two bars both pivoted to the fixed

contact 4 and spaced apart so that their free ends are substantially parallel and capable of engaging opposite sides of a second parallel faced fixed contact 6 carried by the 60 insulator stack 3.

Associated with the contact 4 is a terminal lug 7 for the attachment of a conductor 8 and a similar lug 9 is likewise associated with the fixed contact 6 for the attachment of a 65 second conductor 10; these lugs being preferably integral with the contacts with which they are respectively associated. In order to enclose the fixed contact 6 as far as possible, I mount on the flat face of the terminal lug or plate 9 a hood structure 11 having a base portion 14^a held to said plate by bolts 12, which are also preferably employed to connect the terminal conductor 10 to said contact. 75

This enclosing hood in addition to the base portion 14^a consists of two sides 13 adjacent the opposite parallel flat faces of the contact member 6 and an end member 14 and it will be noted that the upper parts of said 80 sides flare outwardly, as indicated at 15, away from the top of the contact member 6 which projects between them. The inner surfaces of said sides converge toward the outer end of said contact and thereafter extend toward the base plate 14^a parallel with but spaced away from said faces, as indicated at 16. Ribs 16^a project toward each other from the inner surfaces of the sides 13 in a plane substantially parallel with the 90 plane of the end 14 and preferably opposite the middle portions of the contact 6. As a consequence, when the switch blade 5 is swung on the pivot connecting it to the contact member 4 so that it moves toward its 95 closed position, its free parallel elements 5^a pass between the flaring sides 15-15 of the hood and if they are out of alignment with the contact 6, engage one or the other of said ribs so as to be shifted to one side or the 100 other.

As the movement of the blade is continued, it is thus so directed that its elements 5^a ultimately pass into engagement with the opposite parallel faces of the contact member 105 6 and when the switch is fully closed, occupy the relative positions shown in Fig. 6, for example, out of engagement with the ribs 16^a of the hood.

In the present case I have provided operating means including a link consisting of a stack of insulators 19 pivoted to the blade 110

20 and having a rod passing through the channel iron constituting the structure 1. On that side of said structure opposite the insulator stacks 2 and 3 and the blade 5, 5 this rod is connected to the arm 21. This arm is fixed to an operating shaft 22 carried in bearings 23 mounted on the supporting structure 1 and also having fixed to it the similar arms for the other switch 10 blades of the unit. A fourth arm 24 is also fixed to the shaft and to it is pivoted an operating bar or link 25.

With the above described construction it will be appreciated that when the switch is 15 closed, the hood 11 very completely protects the fixed contact 6 and its cooperating end members of the switch blade from accumulations of ice or sleet, since the switch as a whole is customarily used in such positions that the end portion 14 of the hood is either vertical, as shown in Fig. 2, or in some other position in which it and said 20 side members enclose and protect the switch contact 6. It is therefore at all times possible to easily open or close the switch blade 25 without bringing undue stress on any of the parts of the apparatus, since it is not possible for ice to so accumulate as to interfere with its operation.

30 It is moreover to be noted that the hood may be conveniently attached to a switch contact of the ordinary construction, since its base plate 14^a is designed to fit on the flat terminal extension 7 of such contact so 35 that it may be retained in position by the bolts customarily used to clamp a conductor terminal to said extension.

By arranging the shaft 22 with its arms, bearings and operating rod on that side of 40 the structure 1 opposite the switch ter-

minals, blade and conductors, said shaft, etc. in no way affects the striking distance between parts of the switch having widely varied differences of potential and in the event of any of said parts breaking or getting 45 loose their positions are such that they are prevented from possibility of short circuiting or grounding any of the switch parts.

I claim:

1. An electric switch having two fixed contacts; a blade pivoted to one of said contacts and positioned to engage the second contact; with a protective hood for said second contact including ribbed portions for guiding the blade into predetermined engagement 55 with said contact.

2. As a new article of manufacture a hood for a switch terminal having two side members and a back member connecting the same formed to receive within them a switch 60 contact to be protected, said side members having blade-guiding ribs.

3. As a new article of manufacture, a hood for a switch terminal having side members adapted to receive between them a switch 65 contact to be protected, said side members having blade-engaging ribs adapted to engage and guide a switch blade.

4. The combination in a switch of two contacts, a double blade pivoted to one of the contacts and formed to engage opposite sides of the other contact; and a box-like hood on said second contact and having ribs positioned to guide the blade into engagement with the contact, said ribs terminating short of the inner portion of the box-like hood so as to be spaced away from 75 said blade when the switch is in full closed position.

WILLIAM R. HUTTINGER.
